UNITED STATES PATENT OFFICE.

JOSEPH ELON ROSE, OF PORTLAND, OREGON.

PROCESS OF MAKING ARTIFICIAL TEETH.

1,407,484.

Specification of Letters Patent. Patented Feb. 21, 1922.

Application filed October 7, 1920. Serial No. 415,258.

To all whom it may concern:

Be it known that I, JOSEPH ELON ROSE, a citizen of the United States, residing at Portland, county of Multnomah, State of Oregon, have invented a certain new and useful Improvement in Processes of Making Artificial Teeth, of which the following is a specification.

The present invention relates to artificial teeth and has to do more particularly with artificial teeth wherein a crown of gold or other suitable material is provided with a facing of porcelain or like material shaped and colored to simulate a natural tooth.

15 The invention is directed to the production of a new and durable tooth structure.

One object of the invention is to produce an artificial tooth which shall be strong and durable while presenting a neat finish closely simulating a natural tooth. Another object is to produce a novel structure which shall include only a crown and facing which accurately and firmly fit and engage each other. Another object is to so shape the 25 engaging portions of the crown and facing that the latter will be firmly retained in place under all the varied conditions of service.

In carrying out my invention, I provide a crown of one metal throughout which has a front wall comprising a central protruding portion more or less surrounded by a peripheral groove or grooves. The facing of porcelain or like material is shaped so as 30 to accurately fit said protruding portion and grooves and to bear against the same throughout its entire engaging surface. The process for bringing about this result includes several operations. In performing 35 my process I first form a crown so as to fit the prepared tooth and cut away a portion of its face. With the crown in position upon the prepared tooth I then press warm wax into the opening against the tooth. A 40 facing of porcelain or like material is then pressed against the soft wax and the surplus wax trimmed off. The crown, wax and facing may then be removed from the tooth. After the facing is removed from the wax, 45 a mold is made to fit the assembled crown and wax, the crown and wax serving as a pattern. Then the wax is removed from the crown by heating the mold. Then molten gold or other metal is poured into the mold

and the gold occupies the space formerly occupied by the wax. As a result the open face of the crown is closed by a metal wall which accurately fits both the tooth and facing and to which the facing may be readily attached by cement. The facing, itself, is 55 made from a baked porcelain form by grinding it to the desired shape.

It will be seen that in carrying out my invention I am enabled to produce a crown having a porcelain or like facing which may 60 be used on vital teeth. It will also be seen that the metal wall between the facing and the prepared tooth conforms exactly to the irregularities of both the tooth and the facing and thus provides an accurate fit which 65 enables the parts to be readily secured together by cement. Furthermore, the protruding portion of the front wall of the crown together with the peripheral groove and the cooperating surfaces on the facing 70 give the assembled structure a strong and retentive form which greatly strengthens the crown and thereby increases its life and durability. Not only is this true, but by the method I employ, the cutting away of 75 the tooth in preparing it is reduced to a minimum, as it does not need to be shaped so as to fit a particular wall. The construction is such also that the crown may be used as an abutment or anchor for a bridge. 80 There are other features and advantages 85 which will be more particularly pointed out hereinafter while others need not be mentioned since they will be at once apparent to dentists and others skilled in this art. 90

The invention in its various features and aspects will be more fully understood upon reference to the following detailed description, taken in connection with the accompanying drawing, and the scope of the invention will 95 be particularly pointed out in the appended claims.

In said drawing, Fig. 1 is a perspective view of an artificial tooth or crown constructed in accordance with the present invention; Fig. 2 is a vertical section of the crown showing the front cut away so as to provide an open face; Fig. 3 is a similar view of the same crown placed upon the prepared tooth and the open face filled with 100 wax; Fig. 4 is a similar view showing the facing pressed up into engagement with the wax; Fig. 5 is a view of the crown and wax, 105

with the facing removed, secured to the sprue wire in the crucible former; Fig. 6 is a sectional view of a ring mold filled with investment material and the wax burned out, all ready for the pouring of the metal; Fig. 7 is sectional view of the finished crown removed from the mold, its open front now being closed by a metal wall; Fig. 8 is a similar view of the finished tooth 5 showing the facing secured to the outer surface of the metal wall; Fig. 9 is perspective view of the finished crown with the facing removed; Fig. 10 is a section through the crown in position upon the prepared tooth, 10 the section being taken on a plane indicated by the line 10—10 of Fig. 8; Fig. 11 is a perspective view of the crown when in the condition shown in Fig. 2; Fig. 12 is a perspective view of a modified tooth, 15 showing a crown and facing of somewhat different shape; Fig. 13 is a vertical section of the crown of said modified tooth, showing the front of the crown cut away so as to provide the open face; Fig. 14 is a perspective view of the same crown after the metal has 20 been poured to form the front wall; Fig. 15 is a section through the finished modified crown in position upon the prepared tooth, the section being taken on a plane indicated 25 by the line 15—15 of Fig. 13. Throughout these views like characters refer to like parts.

Referring to the drawing in detail, 30 designates a crown of gold or other suitable material which may be made in any preferred way. According to one method of forming a crown the distance around the prepared tooth 10 is measured at the gum line by a fine wire and a strip of gold is then 35 cut according to the length of this wire and its ends brought together and soldered or otherwise secured together so as to form a band. This is then placed upon the tooth and trimmed, festooned and otherwise 40 shaped so as to bring about the desired fit. Obviously other ways of producing the 45 crown may be employed. When the crown is produced its face is cut away so as to provide an opening 11. When the open faced crown is upon the tooth this opening 50 is positioned so as to expose the labial face of the prepared tooth. While the crown is in this position upon the tooth a quantity of warm and plastic wax 12 is placed over 55 the tooth at the point where the opening is and the opening is well filled with the wax. Then the facing 13 which has previously 60 been prepared is pressed against the soft wax until the facing has been brought into its desired position, and the surplus wax is 65 trimmed away. The crown, wax and facing are then removed as a unit from the tooth and a mold is prepared. This mold consists of two parts composed of the usual investment material employed by dentists for

this class of work. One part of the mold, designated 14, is made by filling the interior of the crown while the wax and facing are in position, with the investment material and allowing it to harden or set. This portion of the mold then takes the place of the prepared tooth and has the same shape as the tooth. At this stage the facing is removed from the crown. The other portion of the mold, designated 15, is formed by enclosing the form 14 with the crown 9 and the wax 12 upon it, with investment material in a suitable receptacle. In the case illustrated, the receptacle comprises a ring 16 having a crucible former 17 provided with a central opening for a sprue 19. The form 14 with the crown and wax upon it is then attached to the end of the sprue 19 by the wax. Investment material is applied to the crown upon the sprue in the usual manner, 80 and then the ring 16 is placed on the crucible former, over the crown, and filled with investment. This leaves all the parts carried by the sprue completely surrounded by the investment material 15. When the 85 investment material has set, then the crucible former 17 and the sprue 19 are removed, leaving the sprue canal 20. The ring and its contents are then heated and the wax melted and driven off, leaving the void 21 which is to be filled with molten metal. When pouring the metal, the ring and its 90 contents, as illustrated in Fig. 6, is set on the exhaust stand 22 of a suitable exhausting machine. The exhausting air passes 100 through the pores of the investment material and causes the molten metal, as it is poured, to enter all portions of the void 21. Although I have described the casting operation as one using an exhaust, other casting methods may be employed. When the metal is poured in in this way it fuses with the metal of the crown and provides a solid metal wall 23. This wall closes the opening in the face of the crown 9 and both its 110 front surface and its rear surface have the same shape as did the wax. Consequently the front face of the wall 23 has a surface which closely and accurately fits the rear wall of the facing 13. Similarly the rear 115 face of the wall 23 accurately fits the adjacent surface of the prepared tooth 10. It will be noted also that the front wall 23 comprises a central protruding portion bounded by peripheral grooves 24. These 120 grooves serve to hold the facing upon the tooth with greater certainty, and the walls of the groove, especially that near the incisal edge of the tooth, serve to transmit the strain of impact upon the facing 13 to the 125 crown 9. In this form of the invention, the overlap of the facing about the incisal edge of the crown greatly improves the esthetic appearance of the finished structure. The two facings are to be used for different 130

types of teeth, long and short. When the metal forming the wall 23 has cooled, the crown with its new wall may be removed from the mold. It is then a simple matter 5 to affix the crown to the prepared tooth by cement. In like manner the facing 13 may be secured to the wall 23 by cement.

As before noted I make the facing 13 out of ready-baked porcelain by grinding the 10 same to the desired shape. It will be obvious that crowns of different types of manufacture may be employed. The facings may also be made in different ways and they may also be variously shaped. In any 15 event they should ordinarily be made to cover all the metal of the crown as the tooth is viewed when looking toward the labial surface. In the structure which I have heretofore described, the facing extends over 20 the incisal edge 25 of the crown, overlapping it slightly. As illustrative of a modified arrangement, I have shown a structure in Figs. 12 to 15 inclusive, wherein the crown 9' is provided with an opening 11' which extends 25 only to the incisal edge 25' of the crown. When the crown is completed by the addition of cast wall 23', that wall does not go beyond or include the incisal edge but is of the same length and outline as the opening 11'. 30 In this structure the lower groove 24', or, if you please, the incisal portion of the peripheral groove 24', has a wall 26 which receives the pressure applied to the incisal edge of the facing 13'. There are, as before, the vertical 35 portions of the peripheral groove 24' into which the vertical portions of the peripheral ribs of the facing 13' accurately fit. These grooves in both illustrated forms of the invention co-operate with the corresponding 40 projections or ribs upon the facing to firmly hold the latter in place when subjected to the strains and shocks due to the use of the tooth. In the modified form the wall 26 of the groove 24' receives the greater 45 portion of the strain to which the facing 13' is subjected. In the first form of the invention the strain is taken up more directly by the portion of the wall 23 at the incisal edge 25. Obviously such changes as here disclosed 50 and others of like character may be made without departing from the spirit and scope of my invention. Obviously, too, the configuration of the facing may be greatly varied. The size of the opening may also 55 be varied. Other changes and alterations will suggest themselves to dentists and others skilled in this art. I therefore do not 60 wish to be limited to the precise details disclosed but aim to cover by the terms of the appended claims all the modifications and variations which properly come within the scope of the invention.

What I claim as new and desire to secure by Letters Patent of the United States is:

1. The process of preparing an artificial tooth which includes the operations of forming a crown with an open face, closing the open face with wax, shaping the front of the wax to receive a facing, casting a wall for the crown in place of the wax, and securing 65 the facing to the front of said wall.

2. The process of preparing an artificial tooth which includes the operations of forming a crown with an open face, closing the open face with wax, shaping the front of the 75 wax to receive a facing, shaping the rear of the wax to fit the tooth, casting a wall for the crown in place of the wax, and securing the facing to the front of said wall.

3. The process of preparing an artificial tooth which includes the operations of forming a crown with an open face, closing the open face with wax, shaping the front of the wax to receive a facing, preparing a mold to fit the assembled crown and wax, melting 85 out the wax, and casting a wall for the crown in place of the wax.

4. The process of preparing an artificial tooth which includes the operations of forming an open faced crown and positioning the same upon a prepared tooth, closing the open face by wax pressed against the tooth, pressing the facing into the open face against the wax, casting a wall in place of the wax, and finally cementing the crown to the tooth and 95 the facing to said wall.

5. The process of preparing an artificial tooth which includes the operations of forming an open faced crown and positioning the same upon a prepared tooth, closing the open 100 face by wax pressed against the tooth, pressing a facing into the open face against the wax, preparing a mold to fit the assembled crown and wax, melting out the wax, casting a wall for the crown in place of the wax, 105 and finally cementing the crown to the tooth and the facing to said wall.

6. The process of preparing an artificial tooth which includes the operations of forming an open faced crown, positioning wax 110 in the open face to close the same, and casting a wall for the crown in place of the wax.

7. The process of preparing an artificial tooth which includes the operations of forming an open faced crown, positioning wax in 115 the open face to close the same, preparing a mold to fit the assembled crown and wax, melting out the wax, and casting a wall for the crown in place of the wax.

In testimony whereof, I hereunto subscribe my name this 30 day of September, 120 A. D. 1920.

JOSEPH ELON ROSE.
